Hilley.

UNITED STATES PATENT OFFICE.

HERBERT H. BUFFUM, OF LACONIA, NEW HAMPSHIRE, ASSIGNOR TO ESTEY WATCH TOOL COMPANY, OF LACONIA, NEW HAMPSHIRE, A CORPORATION OF NEW HAMPSHIRE.

SPRINKLER-HEAD.

1,255,111.

Specification of Letters Patent. Patented Jan. 29, 1918.

Application filed May 10, 1917. Serial No. 167,803.

To all whom it may concern:

Be it known that I, HERBERT H. BUFFUM, a citizen of the United States, and a resident of Laconia, in the county of Belknap and State of New Hampshire, have invented an Improvement in Sprinkler-Heads, of which the following description, in connection with the accompanying drawings, is a specification, like characters on the drawings representing like parts.

This invention relates to sprinkler heads for automatic fire extinguishers and its object is to provide a device of this nature which will be positive in its action and at the same time sensitive, which may be easily constructed for release under any desired conditions and which will preserve its sensitivity unimpaired for an indefinite time.

My invention will be best understood by reference to the following description of the illustrative embodiment thereof shown in the accompanying drawings wherein:—

Figure 1 is a side elevation of a sprinkler head embodying my invention, partly broken away;

Fig. 2 is an elevation of the head as seen from the right in Fig. 1;

Fig. 3 is a perspective view of the several elements of the bonding link disassembled; and

Fig. 4 is a central longitudinal section through this link on an enlarged scale.

Referring to the drawings, especially to Figs. 1 and 2, I have there shown a sprinkler head comprising a nozzle 5, for attachment to a water conveying system, adapted to be sealed by a valve or cap 7. Rising from the sides of the nozzle member, as best seen in Fig. 2, are the arms of a loop-like frame 9, which carries a boss 11 opposite the cap 7. The boss 11 may carry a distributor 13 in the usual manner. Between the boss 11 and the cap 7 is interposed a strut for normally maintaining the cap 7 in position against pressure in the system, but adapted to be released in the well known manner when subjected to a sufficient degree of heat.

In the form of my invention shown herein the strut comprises two substantially similar bell crank lever members having arms 15 and 17 bearing on the cap 7 and the boss 11 respectively, the arms bearing pivotally one on the other at 19, a point somewhat out of the direct line between the bearing points of the arms 15 and 17 on cap and boss. The two

arms 15 and 17 thus form a toggle joint and the tendency of the pressure in the system to which the head is attached is to lift the cap 9, rocking the two arms on the point 19 and collapsing the toggle. To retain the cap in position the other arms of the bell cranks 21 and 23 extend from the point 19, preferably in relatively divergent directions and their other ends are secured together by a bonding link denoted generally by the numeral 25 and having a peculiar construction which I will hereinafter describe in detail.

The parts which have been so far described are not in themselves new, although they bear a coöperative relationship to the individually novel elements which I shall next describe.

The link 25 may be assembled with the two lever arms 21 and 23 in the position shown in the drawings or the other way up if desired. Preferably, however, it is faced as illustrated relatively to the pivotal point 19. For convenience in description, however, I shall refer to the parts as upper and lower and inner and outer with reference to the position shown in the drawings, the word "inner" being understood to mean toward the pivotal point 19. These words are herein used, however, merely conveniently to identify the parts referred to and not in any definitive sense.

Referring now more particularly to Figs. 3 and 4, the bond 25 comprises three plates secured together by a fusible solder adapted to melt at a relatively low temperature. The inner plate 27 has a lower cross bar 29, permitting it to be hooked over the end of lever 21 and is apertured to provide an upper supporting surface 31. Secured to the plate 27 by means of a fusible solder shown in Fig. 4 by a heavy line, is a locking plate 33, the preferable form of which is seen most clearly in Fig. 3. The plate 33 may have ears 35 adapted to extend down at either side of the cross bar 29 and thus provide a large surface for attachment by solder of the plate 27 without interfering with the introduction of the arm 21 over the cross bar 29. Extending from the opposite end of the plate 33 is a hook member 37 which, as seen in Fig. 4, is offset relatively to the body of the plate and has a bill or point 39 extending at substantially right angles thereto and adapted to enter the aperture 110

in link 27 and bear against the surface 31 thereof in the manner clearly illustrated in that figure.

Attached to the upper arm 23 is a plate 5 41 which has a cross bar 43 adapted to engage the arm and which corresponds in function to the cross bar 29. Herein a single aperture is adapted to form both this cross bar and a supporting surface 45. The plate 10 41, however, is shorter than the plate 27, which, roughly speaking, is equal in length to the combined length of the plates 37 and 35. As seen in Fig. 3 the plate 27 may have ears 45 similar to the ears 35 of the locking 15 plate 33, which will permit it to lap over the plate 41 for a long distance without interfering with the insertion of the arm 23 of the lever under the cross bar 43.

The plate 41 is assembled with the plate 20 27, overlapping the same and lying flat against the outer surface thereof with the apertures adjacent the surfaces 31 and 45 registering as shown in Fig. 4. The plate 41 is preferably secured in this position by 25 means of fusible solder shown in the figure by a heavy line. The offset hook portion 37 of the locking plate 33 extends over the surface 45 and beneath the surface 31 as will be readily understood from inspection 30 of Fig. 4, thus providing a positive connection between the two plates 27 and 41, so long as the locking plate 33 is retained in the position shown. It will be noted that the plate 41 lies in substantially the same 35 plane as the body of the plate 33 and since, as seen in Figs. 2 and 3, the plates are of the same width, a compact assembly is provided having but two thicknesses of metal which thicknesses are of substantially the 40 same form and have comparatively smooth surfaces. In other words, there are comparatively few shoulders on which solid particles and moisture might gather and which would tend to permit rusting of the 45 parts in such a way that their release when the solder was melted would be impeded or prevented.

Referring to Fig. 4 it will be apparent that if the solder between the various parts 50 is loosened the pull on plates 41 and 27 will develop a turning moment on the hook 37 which, because the body of the same is no longer securely fastened to the plate 27, will rock in a counterclockwise direction 55 and permit the two plates 27 and 41 to fall apart. The fact that the hook 37 terminates substantially flush with the inner surface of the plate 27 without any projecting or overlapping part, permits it to readily 60 disengage from the apertures of the two plates and thus allows the whole structure to fall away from the stream of water coming from the nozzle 5. Furthermore, since the tendency is for the suspension 65 points of 41 at 43 and 45 and the bearing

point of 27 at 29 to move to the same straight line, the plates 27 and 41 will tend to diverge at the top, viewing Fig. 1.

I am aware that prior to my invention it has been proposed to make tension links for 70 use under direct longitudinal tension from three plates one of which was a locking plate comparable to the plate 33. In all these structures with which I am acquainted, however, the locking plate was secured to 75 the plate corresponding to the plate 41. Under these circumstances but one of the soldered joints had a maximum of effectiveness and it was possible to break away the plate corresponding to the plate 27 and unseat it from the flange of the locking member corresponding to the hook 37 quite apart from the condition of the other solder joint. For example, from Fig. 4 it will be seen that if the plate 33 were not in the position 85 shown the lower part of the plate 27 might be rocked to the left breaking away at its upper part from the plate 41 and the bond thus parted. Under ordinary conditions, of course, the various joints would be designed 90 to release at one and the same time but temporary softening of one might cause a slight creeping or minute particles of rust or the like might cause a slight degree of resistance at one joint and consequently unbalance 95 the effect obtained. By securing the locking plate 33 to the member 27 the shearing strain due to the longitudinal pull on the bond is equally distributed on the two joints and thus the full strength of the whole area 100 of soldered joint is rendered effective.

From my description just given in which I have briefly referred to a few of the advantages obtained by the design of link shown and especially in connection with the 105 sprinkler head illustrated, it will be clear that not only is it a neat and serviceable device which will not be likely to deteriorate when in use by rusting of the parts, but is one in which each element acts with the 110 maximum effectiveness and wherein the valve is securely held in position until the time for release comes, which release is sharply effective.

Having thus described my invention, what 115 I desire to secure by Letters Patent is:—

1. In a sprinkler head having a valve and frame, retaining means for the valve comprising levers having arms engaging valve and frame which cooperatively form a toggle and also having relatively divergent retaining arms and a bond between said latter arms comprising an inner plate connected to one arm, an outer locking plate secured to said first mentioned plate by 120 fusible solder and having a hook-like extension which has a bill extended substantially at right angles entering and terminally supported by said first plate and another plate connected to the other arm hav- 125 130

- ing a crossbar engaging and suspended by said extension, said first mentioned plate engaging said last mentioned plate at the inner side thereof and supporting the same throughout the major portion of its length. 5
2. In a sprinkler head having a valve and frame, retaining means for the valve comprising levers having arms engaging valve and frame which cooperatively form a toggle and also having relatively divergent retaining arms, an outer link connected to one retaining arm comprising two substantially coplanar plates having a hook and eye connection and an inner plate connected to the other arm lapsing on and secured by means of fusible solder to both outer plates of the link throughout substantially equal lengths, said inner plate having a transverse portion engaging the hook which hook terminates substantially flush with the inner surface of the plate. 10
3. A device of the class described comprising, in combination, a plate, a second plate lapsing on the first, the two plates having registering apertures, a locking plate having a flat body portion applied to said first mentioned plate and lying substantially in the plane of the second plate and also having an offset hook portion entering through said registering apertures and fusible solder securing together said parts, said several plates being of equal width and forming a 15
- compact assembly comprising two thicknesses of metal of substantially equivalent form and having comparatively smooth 35 surfaces. 20
4. A device of the class described comprising a plate having engaging means, a locking plate secured to said first mentioned plate by fusible solder and carrying a hook-like extension having a bill extended at substantially right angles entering and terminally supported by said first plate, and another plate having engaging means and also having a cross bar engaging and suspended 40 by said extension. 45
5. A device of the class described comprising a plate having engaging means, a locking plate secured to said first mentioned plate by fusible solder and carrying a hook-like extension having a bill extended at substantially right angles entering and terminally supported by said first plate, another plate substantially coplanar with said locking plate having engaging means and a 50 having a cross bar engaging and suspended by said extension, the first mentioned plate extending over the last mentioned plate and secured thereto by fusible solder throughout a substantial area. 55

In testimony whereof, I have signed my name to this specification.

HERBERT H. BUFFUM.
